CLAIM

The ornamental design for a sock with nonslip parts, as shown and described.

DESCRIPTION

FIG. 1 is a top plan view illustrating an interior of a sock with nonslip parts in a collapsed state in accordance with a first embodiment of my new design;

FIG. 2 is a left side elevational view thereof;

FIG. 3 is a right side elevational view thereof;

FIG. 4 is a front elevational view thereof, where a rear elevational view is identical;

FIG. 5 is a top plan view illustrating an exterior of the sock with nonslip parts in the collapsed state in accordance with the first embodiment of my new design;

FIG. 6 is a bottom plan view thereof;

FIG. 7 is a cross-sectional view along the line 7-7 in FIG. 5;

FIG. 8 is a front and left perspective view illustrating the sock with nonslip parts in a three-dimensional, erected state in accordance with the first embodiment of my new design;

FIG. 9 is a top plan view illustrating an interior of a sock with nonslip parts in a collapsed state in accordance with a second embodiment of my new design;

FIG. 10 is a left side elevational view thereof;

FIG. 11 is a right side elevational view thereof;

FIG. 12 is a front elevational view thereof, where a rear elevational view is identical;

FIG. 13 is a top plan view illustrating an exterior of the sock with nonslip parts in the collapsed state in accordance with the second embodiment of my new design;

FIG. 14 is a bottom plan view thereof;

FIG. 15 is a cross-sectional view along the line 15-15 in FIG. 13; and,

FIG. 16 is a front and left perspective view illustrating the sock with nonslip parts in a three-dimensional, erected state in accordance with the second embodiment of my new design.

The broken lines show portions of the sock with nonslip parts that form no part of the claimed design.
